HOSIERY FINISHING AND SORTING RANGE
Rufus K. Smith and John J. Edwin, Charlotte, N.C., as
signors to Chadbourn Gotham, Inc., Charlotte, N.C.,
a corporation of North Carolina

Filed Apr. 16, 1965, Ser. No. 448,700
27 Claims. (Cl. 209—73)

This invention relates to apparatus for boarding knit textile products, and more particularly to a boarding range wherein stockings on forms, or boards, are carried automatically to a retort and to inspection, measuring and stripping stations. The invention concerns the several mechanisms which make up the complete range.

The present practice in mills in handling hosiery for boarding after knitting, is to manually pull the knit hose onto flat boards, or forms, having an outline conforming to the desired shape for the finished stocking, and put groups of the so-mounted stockings into a retort for dyeing or for steaming and drying. After this process is completed, the forms are removed from the retort and the stockings manually stripped from them. The stockings are inspected for defects, manually measured for length, and sorted into piles according to length. This is a slow procedure and requires many workers to carry out.

Automatic boarding and stripping arrangements have been suggested, and a number of proposals have been made for automatically carrying stockings on boarding forms to a plurality of operating stations. None of the proposals, however, have met with sufficient success to be accepted for general use in the industry.

The principal object of the present invention is to provide an improved boarding range which will automatically assemble groups of forms with stockings on them, insert the groups into retorts, remove the groups from the retorts, separate the groups into spaced, single forms, and carry the spaced forms individually to an inspection station, a length determining station, to one stripping station, of a group of stripping stations, selected by the length-determining station where the stocking is stripped from the form, and then return the empty forms to a stocking loading station.

A more specific object is to provide, in a boarding range of this kind, improved means for gathering stocking-fitted forms into groups for treatment, treating the groups, and separating the groups of forms into widely spaced individual forms for travel along the range in spaced relation.

Another object is the provision of a boarding range having an improved drive mechanism for moving the forms along the range in a series of steps.

A further object is to provide improved means for determining the length of a stocking by an electrical scanning means.

It is also an object to utilize the scanning means to determine the stripping station at which each stocking is to be removed from the form.

Another object of the invention is to provide a boarding range having improved overall control means.

Yet another object is to provide improved means for stripping stockings from forms.

An even more specific object is the provision of an improved rail section for track which will change shape as required to follow rollers of a carriage during orientation change of the carriage.

Still another object is to provide novel carriers for transporting the stocking forms, on boards, along the range.

Other objects of the invention will become apparent from the following description of one practical embodiment thereof, when taken in conjunction with the drawings which accompany, and form part of, this specification.

In the drawings:

FIGURE 37 is a perspective view of one of the board carriers;

FIGURE 38 is an exploded perspective of the carrier;

FIGURE 39 is a horizontal section taken on the line 39—39 of FIGURE 37, showing the means to hold boards in adjusted positions of orientation;

FIGURE 40 is a schematic perspective view of the carrier transporting drive;

FIGURE 41 is a diagrammatic view illustrating the cams for coordinating operation of the apparatus;

FIGURE 42 is a circuit diagram showing the control of the carrier transfer area at the loading station;

FIGURE 43 is a circuit diagram illustrating the control circuit for loading and unloading the retorts;

FIGURE 44 illustrates diagrammatically the scanning heads and the commutator at the measuring station;

FIGURES 45A and 45B taken together represent diagrammatically the electric controls for setting the memory drum and coordinating the measuring and stripping stations; and

FIGURE 46 is a logic diagram for length classification of stockings at the measuring station.

General layout

The improved boarding range includes a suitable supporting frame 1 that carries means defining an endless path 2 for a plurality of carriers 3 on which stocking forms, or boards, 4 are mounted. The frame also carries means for advancing the carriers step-by-step along the path in predetermined order, and at predetermined speed, to bring each carrier with its stocking form sequentially to each of a plurality of operating stations located in spaced arrangement along the path. These stations include, in order of sequence around the path, a form, or board loading station 5, a form accumulating station 6, a retort station 7, a form separating station 8, an inspection station 9, a stocking length-measuring station 10 and a stocking stripping area 11 which contains a plurality of stocking stripping stations 12 spaced longitudinally along the carrier path. The entire operation is synchronized by means of a controller 13.

As empty forms on carriers 3 arrive at the loading station 5, one or more operators will manually draw stockings to be boarded onto the forms and smooth them out according to conventional loading procedure. The stockings can be either dyed or in the greige. As will be described in detail, the forms in this area are spaced apart a greater distance than on other parts of the path to pro-

vide the operators with the space and the time required for loading.

Loaded forms will be carried from the loading station to an accumulating area, or station, 6 where the stocking-fitted forms will rest until a group of predetermined number have been assembled in close formation, whereupon the assembled group will be moved from the accumulation station to a position of readiness for loading into a retort.

The retort station 7 will contain one or more conventional retorts in which the stockings can be steamed. Normally, the stockings on the boards, or forms, are pushed onto a track carried by the retort door. The retort closes and begins its steaming cycle. When the cycle is completed, the door opens to a position in alignment with the carriage path and the group of forms containing the treated stockings are pushed off the retort door track into the carriage path. The next group of forms is loaded onto the door track, and the door is closed for the retort to begin another operating cycle.

The group of processed stockings are moved to the station 8 where they are to be separated for continued movement along the carriage path in spaced relation to one another. In the present apparatus, the carriers and forms are picked up singly by the transporting means, with the leading carrier and form of the group, in the direction of movement along the path, being moved away from the remainder of the group each step of movement of the transporting means. Eventually, all the forms of the group will be arranged in spaced succession along the carriage path.

The forms, therefore, arrive singly at the inspection station 9. During all of the operations previously mentioned, the forms have been in vertical position. Just prior to arrival at the inspection station, each form is rotated to horizontal position, to project outwardly from the endless carriage path to facilitate examination by an inspector. The forms are pivotally mounted in the carriages, as will be described, so that the forms can be turned over to examine each side of the mounted stocking.

After leaving the inspection station, the forms arrive at the stocking measuring station 10 where the stockings are measured by electronic scanning, and means set into operation as a result of the scan to select a stripping station 12 for removal of the stocking when the form reaches the selected station. This is accomplished by electrical circuits and instrumentalities housed in a cabinet 14, and through a memory drum 15 controlled from the cabinet 14. In other words, when a scanning head 50 moves over the top edge of a stocking at the measuring station 10, signals are sent to the control cabinet 14 which sets the memory drum 15, to cause actuation of the stripping station 12 for stockings of the measured length when the measured stocking reaches the selected 55 stripping station.

When the form carrying the measured stocking arrives at the stripping station 12 designated for removal of stockings of this particular length, a gripper will grasp the stocking adjacent the heel and toe, strip it from the form 60 and deposit it upon a receiving table 16. The stockings will accumulate in piles of stockings, each pile containing stockings of a single length, adjacent each of the stripping stations. The piles of accumulated sorted stockings can be removed from time to time.

Following removal of the stockings, the forms will be rotated to again assume a vertical position, and be carried by the transporting means back to the loading station to repeat the cycle.

70 Loading station (see FIGURES 1A, 1B, 2, 3, 5, 6, 7, 8, 9 and 10)

The loading station 5 may take different forms for different installations. However, for convenience in using two loading operators, and for purposes of the present disclosure, the station is shown as comprising a pair of

laterally spaced, parallel tracks 17 and 18. In other words, the carrier path is split through the loading station, and carriers bearing empty forms moving along the return track 19 are shunted in alternation to the tracks 17 and 18 by means of a transfer mechanism 20. It will be obvious that if the empty forms are carried in equal spaced relation along the return track 19, they will be spaced at twice that distance apart on the loading tracks if the forms are moved along the loading tracks at the same speed as on the return line.

The transfer mechanism is supported upon the frame 1, which, at this point, has outer and intermediate legs 21 and 22. A table, or platform, 23 is mounted on these legs. At spaced points at the ends of the table there are vertical supports 24 and 25 which carry transversely extending, parallel, horizontal carriage rails 26 and 27. A transfer carriage 28, consisting of a carriage table 29 and rail-followers 30, is mounted on rails 26 and 27 for reciprocating movement therealong. The carriage has a pair of double brackets 31 and 32 in alignment longitudinally of the carriage and fixed to the carriage table 29. The brackets each have a pair of vertical arms, 33 and 34, with each arm supporting a length of track. The track lengths supported by arms 33 of bracket 31 form a transfer track section 35 for mating continuation of the empty track when the transfer carriage is in one position, and for mating continuation of the loading track section 17 when the carriage is in its other position. The track lengths supported by arms 34 of bracket 32 form a transfer track section 36 for alternate registry with the empty track 19 and the loading track section 18. Thus, when the carriage is in one position transfer track section 35 will be in alignment with empty track 19 while transfer track section 36 will be in registry with loading track section 18. When the carriage is at its other limit of movement along carriage rails 26 and 27, transfer track section 36 will be in alignment with empty track 19 and transfer track section 35 will be in registry with loading track section 17. This arrangement will permit loading an empty form from the empty track onto one of the transfer track sections and unloading an empty form from the other transfer track section onto one of the loading track sections when the transfer carriage is in each of its at rest positions.

The transfer carriage is moved to its two positions by means of a double-acting fluid cylinder assembly 37. Cylinder 38 of this assembly has one end anchored to the frame table, or platform, 23, as by the bracket 39. The piston rod 40 of the assembly is connected to the underside of carriage 28 by a suitable connection 41. Aligning stops 42 and 43 are connected to the outer track members of the respective transfer track sections 35 and 36 for alternate abutment with the respective track members of the empty track 19. Switches 44 and 45 are mounted on the carriage 28 adjacent the two transfer track stations in position to be struck and actuated by forms moving from the empty track onto the transfer track sections. Switch 44 will initiate an extending movement of cylinder assembly 37 to move transfer track section 35 from alignment with empty track 19 to registry with loading track section 17. As the carriage arrives at this position, it will operate a switch 46 to initiate movement of a form-ejection cylinder 47 to push the form from transfer track section 35 onto loading track section 17. As the form moves onto track section 17 it will strike switch 48 adjacent track 17 and cause ejection cylinder 47 to retract. During the retraction of cylinder 47, a feed chain 49 (to be described) will carry another form from the empty track onto transfer track section 36 where it will strike switch 45 and cause operation of cylinder assembly 37 in a retracting direction to move the transfer carriage and bring transfer track section 36 into alignment with loading track section 18. As this position is reached, carriage 28 will strike switch 50, initiating operation of a second ejection cylinder 51 in alignment with

track 18 to push the form from transfer track section 36 onto track 18. As the form moves onto track 18, it will strike switch 52 reversing the action of cylinder 51 to retract its plunger.

It is very important that empty forms, or boards, on entering the loading station tracks be properly oriented to facilitate drawing stockings over them. As operators will be positioned on each side of the loading station, one for loading boards on track 17 and one for loading boards on track 18, the forms on the tracks should be upright with the toe portion toward the operator. This means that boards on the two track sections should be oppositely disposed with the toe portions pointed outwardly.

To this end, the boards 4 are pivotally mounted on the carriers 3, as will be described later in detail. Normally, the boards are moving along the return track 19 so oriented that the flat sides of the board are parallel to the tracks with the toe portions turned to the rear with respect to the direction of travel. Each board is mounted in a seat member 53 swivelly carried by the carrier 3, and the seat member has a depending guide roller 54 by means of which the orientation of the board can be controlled. As shown, the guide roller is located on the opposite side of the swivel 55 from the toe portion of the form. In other words, if the seat member is positioned longitudinally of the tracks and the board toe is in a trailing position, the guide wheel 54 will be at the leading end of the board seat member. This is the normal position of the forms when moved from the return track 19 onto the transfer track sections 35 and 36 on the transfer carriage 28.

In order to orient the boards, there is a guide 56 mounted at the transfer position. It consists of a support 57, fixed to frame platform 23 and having an end 35 overlying the transfer carriage in alignment with the center line of the discharge end of the return line 19. The guide proper 58 is attached to the upper, free end of the support 57, and has the form of a V-shaped receiving throat 59 for carrier guide wheels 54, with the sides 60 and 61 of the throat diverging convexly and horizontally from the center of the V. As the guide wheels 54 are at the leading ends of the carriers as the carriers are moved onto tracks 35 and 36, the guide wheels will enter the guide throat (as shown in dotted lines in FIGURE 5). As the transfer carriage moves, the guide wheel will be restrained by the guide and forced to follow the cam surface of the side 60 or 61 of the guide, depending upon the direction of movement of the transfer carriage. This will rotate the board seat member 53, and the board it carries, through ninety degrees to arrange the board transversely to the direction of the endless path. As, in each instance, the guide roller will be restrained by the guide, the toe portion of the boards will be turned to face the operators at the sides of the tracks 17 and 18.

Where the carriers with properly oriented boards are moved onto the track sections 17 and 18, they are picked up by carrier chains 62 and 63, which extend the length of the loading station. As chains 62 and 63 are identical, the same reference characters will be used for both. The chains are trained over sprockets 64 on a shaft 65, journaled on the frame adjacent the transfer area, and sprockets 66 on shafts 67 journaled at the juncture of the loading and accumulating stations. Shaft 65 is rotated, by means to be described, to move the chains step-by-step in synchronism with the movement of the feed chain 49. As mentioned above, the shuttling of the forms alternately to tracks 17 and 18 will result in spacing the forms on tracks 17 and 18 at twice the distance of those on return track 19 and the feed chain. This will result also in having the forms staggered on the two tracks, with those on one track occupying longitudinal positions intermediate those on the other. The carriers and boards are moved along tracks 17 and 18 by means of dogs 68 carried at spaced intervals by chains 62 and 63. The dogs engage the carriers and pull them along the tracks.

During passage of the boards along the tracks at the loading station, stockings are pulled over them and smoothed down in conventional manner by the operators at the respective tracks. Due to the doubled spacing of the boards in this area, the operator will have a time interval equal to two steps of advance of the chains to load each board. This provides ample time.

Accumulating station (see FIGURES 1B, 3, 8, 9, 10 and 11)

After the boards are loaded, they are carried by chains 62 and 63 to the accumulating station 6. In this area, the loaded boards are collected to provide groups of proper number for later insertion into the retorts for processing.

The accumulating station extends from the exit end of the loading station, and includes extensions 69 and 70 of tracks 17 and 18, projecting beyond the sprockets 66, and shiftable track sections 71 and 72 in alignment, respectively, with the projections 69 and 70 of tracks 17 and 18, upon which groups of carriers and boards accumulated on the projecting track extensions are moved when ready for insertion into the retorts.

As the carriers being moved along tracks 17 and 18 by contact of dogs 68 on chains 62 and 63, they eventually reach the area of sprockets 66 and are pushed forward by the dogs and released as the chains begin to turn about the sprockets. Thus, each carrier, in turn, will be released, and each will push the one before it along the extension tracks 69 and 70 to accumulate in a contacting group on the tracks. When a group of predetermined number has been accumulated, the leading carrier will contact, and operate, a switch 73 on track 17, or a switch 74 on track 18, as the case may be. The switches control power cylinders 75 and 76 located beneath the respective tracks at the accumulation station, and when one of the switches is actuated its respective cylinder will operate to move the accumulated group of carriers from the track extension 69 or 70, as the case may be, onto the aligned shiftable track section 71 or 72.

Power cylinders 75 and 76 are identical. Each has a cylinder 77 fixed to the platform 78 of a carriage 79 upon which the shiftable track 71 or 72 is mounted. The carriage is slideable upon rails 80 extending longitudinally of the carrier path and fixed to the apparatus frame. The carriage carries a trough-shaped guide 81 projecting toward the loading station, in which a slide 82 moves. The slide is connected to the piston rod 83 of the power cylinder and pivotally carries an upwardly spring biased dog 84. When the piston is retracted, the dog will engage the trailing carrier of an accumulated group and move it forward onto the aligned shiftable track section. The spring biased dog can pivot downwardly as the carriers are pushed forwardly by the loading station chains, so that the carriers being accumulated can pass over the dogs.

When the assembled group of carriers are moved forward onto the aligned shiftable track section, the leading carrier will strike a switch 85 or 86, depending upon the track sections, when the group is properly located on the shiftable track, to stop the forward movement of dog 84 and start a reverse movement of the cylinder to return the dog to inoperative position.

Ordinarily, the accumulation on the two track sections will be staggered so that when a group of predetermined number have been accumulated on one track, a group of but half that number will be accumulated on the other track. By this arrangement it will be possible to feed two retorts in alternation, so that while one retort is in operation processing hose, the other can be opened for unloading and reloading.

Retort station (see FIGURES 1B, 3, 4 and 11 to 17 and 19)

The retort station 7 is immediately adjacent the shift-

able track sections 71 and 72 of the accumulation station, and groups of carriers and forms held on these track sections are loaded directly onto the retort doors for positioning in the retorts for processing.

There are two retorts shown, a first retort 87, adjacent the shiftable track section 71 for processing stockings loaded on forms on track 17, and a second retort 88, adjacent the shiftable track section 72 for processing stockings loaded on forms on track 18. The retorts are oppositely arranged on opposite sides of the two track lines with the doors of the retorts in confronting relation. The retorts are of the general nature of the one disclosed in the United States patent to Berger et al., No. 3,162,031, issued Dec. 22, 1964, and that patent can be referred to for a detailed disclosure of the retort structure. For purposes of the present disclosure, it is only necessary to state that each retort has a door 89 supported by a trolley 90 for movement along rails 91 from a closed position to an open, board-unloading position, to an intermediate, open, board-loading position and back to closed position. The door is moved by means of a rack 92 to the several positions. The doors of the retorts operate in alternation, so as to permit loading of the retorts in alternation, and the opening movement of either door is initiated by a signal from the controller 13 (to be described) and the closing of switch 85 or switch 86 depending upon whether retort 87 or retort 88 is to open. This occurs after the stockings on the group of forms in the retort have finished their processing cycle and an accumulated group of carriers and loaded boards are on the adjacent shiftable track section ready for loading.

If, for example, a group of forms ready for loading are on the shiftable track section 71 and the controller 13 has sent the proper signal to retort 87, door 89 of that retort will open. The door supports a retort track section 93 from its inner side, on which a group of loaded boards are held within the retort during processing. The opening door will carry the track section with it, and will continue movement until the retort track 93 reaches a point midway between the track paths 17 and 18 and in alignment with an unloading track 94. When the door reaches this position, it strikes a switch 95 which causes the door to stop, and, at the same time, causes a discharge carriage 96 to move track sections 97 which it carries into contact with one end of the retort track 93, and the unloading track 94 to move into contact with the other end of the retort track.

The discharge carriage 96 is mounted in frame 1 midway between the track lines 17 and 18, and in alignment with the unloading track. The carriage has rail followers 98 which ride upon longitudinally extending rails 99 supported upon the frame. A power cylinder 100, fixed to the frame 1 has its piston rod 101 connected to a leg 102 depending from the carriage, so that operation of the cylinder 100 causes movement of the carriage along the rails. It is cylinder 100 that is actuated by operation of switch 95 to move the discharge track sections into contact with the retort track.

On top of carriage 96 there is a power cylinder 103 that is mounted between upstanding brackets 104. The piston rod 105 of this assembly is attached to a carrier 106 which is a duplicate of the base body portion of carriers 3 but does not have or need a board seat. Carrier 106 is mounted on discharge track sections 97, which are supported upon bracket 107 fixed to the carriage.

With this arrangement, the carriage can be moved to advance the track sections 97 into contact with the retort track sections when the retort door is in unloading position and switch 95 is closed. As the carriage reaches this position, it closes switch 108. As the carriage moves forward, the unloading track 94 also moves into contact with the retort door track and will close a switch 109 when in this position. The closing of switches 108 and 109 actuates cylinder 103 to move carrier 106 off of track section 97 onto track sections 93 in the retort door. Con-

tinued movement of the cylinder will cause carrier 106 to contact the end carrier 3 of the group on the retort door track and push the group from the door track onto the unloading track 94. When the group is wholly on the unloading track, a switch 110 is closed to reverse operation of the cylinder 103 to return carrier 106 to its position of rest. As carrier 106 reaches its retracted position, switch 111 is operated which causes carriage 96 to retract, separating discharge track 97 from the retort door track. The closing of this switch also causes the unloading track 94 to move away from the retort door. Carriage 96 strikes a switch 112 as it reaches its inoperative position, and the unloading track 94 operates a switch 113 as it comes to its retracted position. Operation of switches 112 and 113 will stop movement of carriage 96 and track 94 and start retort door 89 moving toward closed position.

As the door of retort 87 moves away from the unloading position and approaches alignment with the shiftable track section 71, it will hit a switch 114 to stop the door movement with the door track in alignment with track 71. Operation of switch 114 also causes shiftable track 71, bearing its accumulated group of loaded boards, to move forward into engagement with the retort door track 93. This movement is accomplished by means of a power cylinder 115 which is fixed to frame 1 and has its piston rod 116 attached to a leg 117 depending from carriage 79. (A similar mechanism, designated by the same reference characters is provided for moving the carriage of shiftable track 72.)

As carriage 79 reaches its forward limit of travel with tracks 71 and 93 in contact, a switch 118 is struck to actuate a charging cylinder 119. This cylinder is fixed to frame 1 and has its piston rod connected to a slide 120 travelling in a guide 121 carried by carriage 79. Slide 120 has a dog 122 pivoted to it, and the dog is yieldably held in raised position by means of a leaf spring 123. (See FIGURES 14 and 15.) As slide 120 is moved forward in guide 121, dog 122 will contact the end carrier 3 of the group on track section 71 and push the group from track 71 onto the retort door track 93. When the charging cylinder reaches its extended position it hits a switch 124 which causes the cylinder to reverse its movement and the carriage 79 to retract, moving the track 71 from the retort door back into contact with the accumulating track 69. When the carriage is retracted it hits a switch 125 that stops the charging cylinder retraction, the carriage retraction and starts the retort door moving toward fully closed position. (A similar charging cylinder and system of control switches, indicated by the same reference characters, is provided for the track section 72.)

When the retort door is fully closed, the new group of loaded boards is within the retort and a switch 126 is actuated by the closing door to start the steaming cycle.

The unloading track 94 is supported upon a carriage 127 movable along rails 128 mounted on frame 1. It is moved from a position in contact with the track 129 at the separating station 8 into contact with the retort door track 93 and back by means of a power cylinder 130, mounted on the frame and having its piston rod 131 connected to a leg 132 depending from carriage 127. The cylinder is actuated as previously described to bring the unloading track to the retort door track where it receives a group of carriers and boards which have been processed. The carriage then moves back to contact the ends of unloading track 94 with the ends of separating track 129.

The closely assembled group of carriers on the unloading track are moved off onto the separating track by means of a lever 133 pivotally mounted in a recess 134 in a block 135 slidable along a rail 136 parallel to the carrier path 2. Lever 133 has a long, carrier-contacting arm 137 and a short, actuating arm 138. In one position of movement, the carrier-contacting arm 137 strikes the back 139 of recess 134 to hold the arm normal to the carrier path 2. In the other extreme position, the

actuating arm 138 contacts the recess back 139 to hold the carrier-contact arm 137 at an angle to the carrier path and removed from a carrier-contacting position. The block 135 is moved along rail 136 by means of a power cylinder 140 which is pivotally in contact on the frame 1 for horizontal swinging movement. The piston rod 141 of the cylinder is coupled to the end of the actuating arm 138 of lever 133.

When the cylinder is to be extended, the pressure of the piston rod on lever arm 138 causes the lever to rock about its pivot 142 until arm 138 strikes the back of recess 134, whereupon the pressure is transferred through the arm to the block to push it along the rail. During this movement, the carrier-contacting arm 137 is canted (as seen in FIGURE 17) and will pass by the group of carriers on the unloading track. Reversal of the cylinder 140 will exert a pull upon lever arm 138 and swing the lever about its pivot until arm 137 strikes the back of recess 134. As this stops swinging movement of the lever, the block will be drawn along the rail as the cylinder retracts. The lever arm 137, in this position will engage the rearmost carrier 3 of the group on the unloading track and draw the group from the unloading track onto the separation track 129.

The cylinder 140 is actuated when carriage 127 moves from its retracted position toward the retort door. In its retracted position carriage 127 is in engagement with a switch 1001, and when the carriage moves the switch operates to cause cylinder 140 to extend. When carriage 127 returns to its at rest position it strikes switch 1001 and causes cylinder 140 to retract.

Separation station (see FIGURES 1B, 3, 16, 17, 18 and 19)

The processed hose on their boards arrive at the separation station 8 in the same closely arranged group formation they acquired at the accumulation station 6 and maintained during their passage through the retort station. It is necessary, however, that for the operation to be subsequently performed during passage about the range that the boards be separated and moved in uniform spaced relation.

To separate the boards, there is a separation chain 143 travelling over sprockets 144 and 145 mounted on shafts 146 and 147 journaled on frame 1. The chain is arranged to follow a vertical path and has a top flight 148 extending in the direction of the carrier path just below the separation track 129. The entire group of carriers moved to the station are positioned over the top flight of the chain. (See FIGURES 18 and 19 particularly.) The chain top flight travels over a platform 149 to hold it level and prevent sagging. The carriers are picked up by dogs 150 pivotally mounted on the chain, and spaced apart the distance required for subsequent operation upon the boarded hose.

If separation is to be had, it is essential that the carriers be picked up singly, and that they be picked up from the leading end of the group. This requires the pick up dogs 150 passing beneath the carriers of the group without engagement until the leading carrier is reached. To accomplish this, a spring cam 151 is provided for each dog to hold the dog depressed during passage beneath the grouped carriers until the leading carrier is reached. Spring 151 is convex and has one end attached to the dog. The opposite end is slidable within a clip 152 carried by the chain. The spring in its unflexed condition will hold the dog elevated so that its leading edge is above the level of the carrier bottom for engagement with the carriers. The convex cam portion 153 of the spring is normally at a higher elevation than the carrier bottom, so that it will contact, and be depressed by, the carriers as it passes beneath them. This will draw down the dog so that it will not contact the carriers, but will pass freely beneath them. The cam portion 153 of the spring is located just far enough in front of the dog to permit the

dog to rise to contact the leading carrier when the cam passes beyond the dog and is released. Thus, each dog will move beneath the assembled carrier group but will rise and engage the leading carrier and move it from the group. This will cause the carriers to be picked up in sequence and moved along the track at spaced intervals equal to the spacing of the dogs on the separation chain.

As the carriers separate from the group and move out in spaced relation they complete their travel along the first leg of the oval endless path 2 and are picked up from the separation chain by a conveying chain 154 to be transported around the end curve of the path to begin travel along the second leg of the endless path.

Chain 154 follows a horizontal orbit and is trained about a drive sprocket 155 and an idler sprocket 156. Sprocket 155 is mounted upon a drive shaft 157, journalled on the frame 1, and sprocket 156 is carried by an idler shaft 158 also mounted on the frame. The operative flight of the chain is guided by idlers 159 arranged in an arcuate path concentric to the curved track path, and by curved guide plates 160 between the idlers. The non-operative, or return flight of the chain could extend directly from sprocket 155 to sprocket 156, but, to provide more clearance within the endless path, another idler sprocket 161 is fixed to the frame midway between the sprockets 155 and 156. Carrier-engaging dogs 162 are fixed to chain 154 at spaced points equidistant to the spacing of dogs 150 on separation chain 143. The operative flights of chains 143 and 154 are so arranged that the dogs of chain 154 engage the carriers just prior to their release by the dogs of chain 143.

It will be remembered that the boards 4 were turned just prior to arrival on tracks 17 and 18 so that the toe portion of each form would project outward relative to the two tracks of the loading station. In other words, the toes would point toward the loading operators standing along the two tracks. The boards on the two tracks, therefore, are reversed. The boards are accumulated in this manner, processed in the retort, and delivered onto separation track 129. Thus, one group of boards at the separation station will have the toes pointed in one direction and the next group will have the toes pointed in the opposite direction. It is important, as will appear, that all boards arrive at the inspection station arranged with the toes in the same direction and the boards in line with the line of travel rather than normal to it as before.

In order to properly orient the boards, guides 163 are carried by frame 1 and extend over the tracks just where the carriers leave the separation station. This guide will be contacted by the depending guide rollers 54 of all boards and rotate them ninety degrees to position the boards in the plane of the path of travel with the toes at the leading edge. The guide roller will contact the guides at one side or the other of the track, depending upon their original position, and the rollers will be restrained to turn the board so that the roller is at the trailing edge. The boards will then be carried around the curved track by the chains 154 to the inspection station 9.

Inspection station (see FIGURES 1B and 21 to 24, inclusive)

During loading, accumulating, processing, unloading and separating, the boards have been held upright. For inspection, measuring and stripping, however, it is desirable to have the boards horizontal. To this end, the carrier track is provided with a turndown section 164 just ahead of the inspection station 9.

The turndown track section is designed to rotate the carriers 3 through ninety degrees, thus swinging the boards mounted on the carriers from vertical to horizontal. To accomplish this, the outer rail 165, at the turndown position, is carried straight through the section. The inner rail 166, however, is flattened and curves upwardly and outwardly following the curving path described by a carrier 3 in turning ninety degrees while

maintaining contact with the straight outer rail 165. At the end of the turndown section, rail 166 lies directly over rail 165, is parallel to it and is spaced from the same distance as before.

5 Due to the fact that the carrier position is differently oriented and at a higher level, another conveyor chain 167 picks up the carrier, and the carrier is released from the chain 154. Chain 167 passes around a drive sprocket 168 mounted on a shaft 169. The upper, operative flight of the chain has an inclined path 170 from the sprocket 168 to an idler 171, which inclined path coincides with the turndown section of the track. From the sprocket 171, the chain flight follows a level, horizontal path 172 through the inspection, measuring and stripping stations 10 to pass around an idler sprocket 173 at the far end of the stripping area 11. The chain return flight is from sprocket 173 to drive sprocket 168. This chain has carrier-engaging dogs 174 spaced along with the same spacing as on the chain previously described. Thus, the dogs 174 of chain 167 can pick up the carriers from chain 154 and convey them smoothly along the carrier path.

15 The inspection station is adjacent the turndown section of the track. The boards will arrive at the inspection station extending horizontally outward from the track 25 with the flat side of the board horizontal and the toe pointed in the direction of travel along the path. There 20 will be an operator at the inspection station who will examine the upper side of stockings on the boards for flaws. After the upper side is examined, the board is turned over so that the other side of the stocking may 30 be inspected. This places the toe of the board at the trailing side of the board in the proper position for stripping, yet only one turning movement is required of the operator.

35 If the stocking is without flaws, the inspector takes no action, but if the stocking contains flaws the operator will press a reject button 175 which will set into operation mechanism (to be described) to strip the stocking from the board when the board arrives at the reject stripping 40 station. It will be apparent that more than one reject station could be employed, and the operator could have more than one reject button. For example, the rejects could be separated into stockings which are wholly unusable and those which can be used after mending.

45 *Measuring station (see FIGURES 1B, 21, 23, 25 and 26)*

After chain 167 has completed its pause to allow 50 inspection of a stocking, it moves one step to bring the carrier and board with its inspected stocking to the measuring station 10. Here, the stocking is scanned electrically and apparatus is set in motion for stripping the measured stocking from the board when it reaches the stripping station for stockings of the measured length. As the boards are all the same size and positioned at the 55 measuring station in identical fashion, it is only necessary to determine the location of the stocking top on the board to know the length of the stocking.

Any desired program for selection and rejection may 60 be set up, but for purposes of disclosure it will be assumed that all stockings within a two inch length band above a predetermined minimum length will be accepted unless there is too much difference between the lengths of the two sides of the stocking. If this difference is too great the stockings will be rejected. If the stockings are shorter 65 than the minimum length they will be rejected as too short. If they are more than two inches longer than the minimum they will be rejected as too long. Those within the two inch band of acceptable variation may be divided into groups having not more than one-quarter inch length variation. In other words, each quarter inch within the two inch acceptable band will represent a size division, and the stockings will be measured to determine their size.

70 As it is important to measure both sides of the stocking to learn if there is an unacceptable length variation

between the sides, a scanning yoke 176 is provided to carry opposed electric eyes 177 and 178. These are positioned to move on opposite sides of the board carrying the stocking to be measured.

The measuring apparatus is supported upon a beam 179 carried by frame 1 to overlie the carrier track and boards carried to the measuring station. The outer end of the beam is fixed to a portion of the stripping table 180. Beam 179 has bearing blocks 181 mounted on it to slidably receive one arm 182 of the scanning yoke 176. The bearing blocks have square openings to receive the square arm 182 and hold the yoke against rotation during sliding movement through the blocks. The yoke is moved by a power cylinder 183 which is attached to the arm 182. The cylinder has a piston rod 184, and the end of the piston rod is connected to a bracket 185 mounted on one of the blocks 181. The power cylinder moves the yoke so as to move the electric eyes 177 and 178 away from the track, longitudinally of the board, and over the stocking welt. When the cylinder has completed its movement, a switch 186 is actuated to release the cylinder and allow the yoke to return to inoperative position by means of a spring 187. The spring is attached to the arm 182 and one of the bearings 181. As a carrier 3 arrives at the measuring station, a switch 188, to be described, is actuated to stop the conveyor and initiate action of cylinder 183.

Yoke 176 has a second arm 189 which is connected to arm 182 by a bridge member 190. Arm 189 extends parallel to arm 182 and carries electric eye 178. Electric eye 177 is mounted on arm 182 above electric eye 178, so that the scanning eyes are directly opposed.

Arm 182 of the scanning yoke 176 carries a commutator rod 191 which carries brushes for movement over rows of contacts of a commutator 192 mounted on beam 179. As the yoke is moved, the brushes move over the commutator contacts. Signals from the electric eyes are carried to the contacts by the brushes, with the change in signal as the electric eyes pass from the polished boards 4 onto the stocking welt being registered through the commutator contacts with which the brushes are at that time in contact. The details of the commutator and the control system will be described later.

The signal change from the electric eyes will set into operation certain equipment, to be described, which will activate a stripping station for stockings of the measured length when the measured stocking reaches that station.

Memory device (see FIGURES 1B, 23, 27, 28 and 29)

The signal from the scanning head as to the length category of the measured stocking will be put into a storage device for use in activating a selected stripper station to strip the stocking from the board when the board arrives at the station. Memory devices of different kinds can be used successfully.

For purposes of this disclosure, a memory belt, or drum, 15 is shown. This device is enclosed in a suitable housing 193, and consists of a wide belt 194 composed of a pair of chains 195 held in spaced relation by means of transversely extending rods 196 which are arranged in parallel, spaced relation. Chains 195 are trained about drive sprockets 197, mounted on a drive shaft 198, and idler sprockets 199 mounted on shaft 200.

The rods 196 may be considered as being arranged in groups of three. The center rod of each group carries a plurality of spring actuating fingers 201, 202, 203, 204, 205 and 206, equally spaced along the rod, and freely pivoted at one end to the rod. The fingers are arcuate longitudinally, and, in their positions of rest, have their free ends resting upon an adjacent rod with the concave sides of the fingers uppermost. The rod supporting the free ends of the fingers in the inoperative, or at rest position, is the trailing rod of the group relative to the direction of movement of the belt. At certain times, in response to signals from the controls activated by the scanner head, 75

as will be described, selected pairs of fingers of the plurality mounted on the center rod of each group will be rotated 180° about their pivot rods to have their free ends rest on the leading rod of the group. In this position, the convex sides of the fingers will be uppermost to lie in the path of certain switches, to be described, to actuate those switches.

The fingers are moved to operative position by means of solenoid-actuated plungers 207, 208, 209, 210, 211 and 212 mounted on a plate 213 in alignment with the respective finger positions along the belt rods. The plungers are slideable in guides 214 and 215 carried by the plate 213, and each is connected to the armature of one of the solenoids 216, 217, 218, 219 and 220 and 221. The plungers are biased to raised position by means of coil springs 222, 223, 224, 225, 226 and 227, and are normally held in retracted, inoperative position by having the solenoids normally energized. The belt will be moved in increments equal to the spacing between center rods of the groups in timed relation to the movements of the board carrier conveyor chains, as will be described, and pause with a row of fingers directly over the plungers. During the pause, the scanning head will move over the top of a stocking at the measuring station and send appropriate signals to the solenoids of the memory drum. The selected pair of solenoids will be deenergized, releasing their plungers to spring upward under the influence of their biasing springs and strike the overlying fingers and move them to operative position.

The belt will move step by step as the boards move step by step, along the stripper area 11. When the board carrying the measured stocking arrives at the stripping station next adjacent the stripping station selected for stockings of the measured length, the memory belt with its set fingers will have arrived at a point adjacent a pair of switches 228 and 229 located in switch lanes 230 in line with the fingers positioned above the memory belt. The operating arms of these switches will lie in the paths of movement of the set fingers on the belt, so that upon the beginning of the next movement of the board along the stripping area, and the simultaneous movement of the memory belt, the set fingers will operate the switches to initiate outward movement of the gripper at the selected stripper station to position the grippers at the stripping position when the board arrives, and stops, at the selected position. There will be as many pairs of switches in the lanes 230 as there are stripping stations, with the pairs of switches being spaced a distance equal to an increment of movement of the memory belt. The pair, or pairs, of switches operated on any movement of the belt will depend upon the setting of the fingers for the measured stocking lengths.

After passing through the switch area, the belt will pass around sprockets 199 to return to drive sprockets 197. As the belt passes around sprockets 199, the fingers will swing down by gravity to hang below the belt (see FIGURE 27). As the belt moves upward around sprockets 197, the fingers will settle by gravity into their inoperative positions. This provides an automatic reset for the switch-actuating fingers.

Stripping stations (see FIGURES 1A, 1B and 30 to 34, inclusive)

When a board has stopped at the measuring station, and the stocking has been scanned, and the memory drum set, the board is moved forward by means of the conveying chain 167, which will bring the board and its stocking to the first stripping station. If the memory drum has been set for removal of the stocking at this station the gripper head will move out, grasp the foot of the stocking and strip it from the board. If the stocking is not to be removed at this station, it will be conveyed step-by-step along the stripping area until it arrives at the selected station. All of the stripping stations are identical, therefore only one will be described.

The gripping apparatus is supported upon a rail 231 which is mounted at one end on the main frame 1 and projects outwardly over the carrier track having its outer end supported upon an auxiliary frame 232. A gripper head 233 is suspended from a carriage 234 movable along rail 231.

The carriage may be a simple tubular member having a polygonal central opening corresponding to the cross-sectional shape of the rail 231. Any desired form of anti-friction member 235 may be used in the carriage to facilitate movement of the carriage along the rail. A power cylinder 236, fixed to rail 231, has its piston rod connected to carriage 234 to move the carriage along the rail.

Gripper head 233 consists of a U-shaped yoke 237, suspended from carriage 234 by means of rods 238 and having a pair of jaws 239 and 240 pivotal mounted on it. The jaws are T-shaped members with the legs of the T's projecting between the arms of the yoke and being pivoted on shafts 241 and 242 extending between the arms of the yoke. The cross-members of the T-shaped jaws form the gripping portions of the jaws, and each is provided with a plurality of stocking-engaging pads 243 and 244. The pads are inflatable and to this end each has an extendable cover 245 mounted over a retainer 246 seated in a recess 247 in the bottom face of the gripping faces of the jaws. A bolt 248 is threaded through the jaw into the retainer to hold the retainer in its seat and the cover clamped between the retainer and the seat. A passageway 249 through the retainer and the bolt communicates with an air manifold 250 in the jaw and the interior of the pad to provide for inflating the pad. A supply line 251 from a suitable source is coupled to the jaws to communicate with the air manifolds.

Lower gripper jaw 240 will normally hang at downwardly declining angle (as shown in dotted lines in FIGURE 34) when not in use. Upper gripper jaw 239 will be drawn upwardly by spring 252, connected to the jaw and to carriage 234. The at rest angles of the jaws will be determined by the position of a jaw-actuating roller 253 relative to the jaw pivot shafts 241 and 242. The roller is carried by the piston rod 254 of a power cylinder 255 mounted on yoke 237. As the cylinder piston is retracted, roller 253 will be drawn back, crossing the plane of the jaw pivots and causing the jaws to close. As the jaws close, the pads will be inflated, as will be described, and brought into gripping engagement with a stocking on a board. Movement of the piston in cylinder 255 in the opposite direction will cause the roller 253 to re-cross the jaw pivot plane, permitting lower jaw 240 to drop by gravity and upper jaw 239 to rise under the influence of spring 252 and release the stocking.

Normally, the gripper head is at rest at the outer limit of travel of carriage 234 along rail 231. When a carrier 3 with its board and processed stocking arrive at a stripping station immediately adjacent the station at which the stocking is scheduled for removal from the board, the two fingers of the group 201 to 205 of the memory drum which were set when this particular stocking was measured, will be adjacent the switches 228 and 229 which they are to operate. As the conveyor chain 167 begins its next step of movement to move the stocking to the selected stripping station, the belt 194 of the memory drum will also move, causing the set fingers to operate their switches 228 and 229. This, by means to be described, will actuate gripper carriage cylinder 236 to move the carriage from the position of rest to a position where the stocking foot will pass between the jaws of the gripper head, so that the gripper head will be in gripping position when the stocking arrives at the station. Movement of the carrier conveyor is stopped by operation of switch 183, which is the same switch that starts movement of the scanning head at the measuring sta-

tion. Operation of switch 183 also causes the gripper jaws to close and the pads to inflate and operates a time delay relay which causes the stripper carriage to start its return movement drawing the stocking from the board after the pads have inflated and the jaws closed. The carriage will return to its position of rest, and, as it approaches this position, a striker 256 mounted on the carriage will strike, and operate, a switch 257 supported on an arm 258 above rail 231, and the jaws of the gripper head will open and the gripper pads will deflate allowing the stocking to fall full length of the receiving table 16. The table may have an upwardly peaked, or a convex, upper surface to ensure the stocking settling on the table in fully extended condition.

15 *Board elevating track section (see FIGURES 1A, 35 and 36)*

After leaving the station at which the stocking was stripped from the board, the carrier 3 is moved step-by-step through the remainder of the stripping area 11 and to a track section 259 which rotates the carrier to raise the board back to vertical position. Track section 259 is composed of a straight, rigid track member 260, which is a continuation of the lower track member extending through the stripping area, and a flexible member 261 having a reverse curve between its ends, which is a continuation of the upper track member of the previous track section. The rigid member 260 becomes the outer member of the elevating section and the flexible member becomes the inner member.

20 30 The two track members are supported at one end upon the vertically extending arms of an inverted U-shaped bracket 262 mounted on the frame 1 at the end of the stripping area, and at the other end upon the horizontally extending arms of a similar bracket 263, mounted upon frame 1 in a position of orientation ninety degrees displaced from the position of the bracket 262. Intermediate the brackets 262 and 263, there is a bracket 264 mounted upon an inclined platform 265 projecting from the frame 1. The position of orientation of bracket 264 is approximately forty-five degrees from each of the end brackets.

35 40 The use of a flexible element for the track member 261 eliminates the necessity of using an element of complex shape and curvature to correspond to the paths described by the rollers of the carriers 3 in rotating from one position to another, as the flexible track member will automatically conform to the roller path as the carrier moves along it.

45 50 In order to support the long upper flight of conveyor chain 167 during its passage through the measuring station and stripping area and along the board elevating track section, a channel 266 is provided, mounted on the brackets carrying the track. The channel follows a horizontal path through the stripping area but declines slightly as at 267, along the board elevating track section so that the chain dogs 174 will retain contact with the board carrier during rotative movement of the carrier.

55 60 After completing the elevating movement, the carriers with their boards move onto the return track 19, where a return conveyor chain 268 picks up the carriers from chain 167 and transports them around the curved return path to the transfer carriage feed chain 49. Chain 268 follows the arcuate track by passing around rollers 269. The end sprockets 270 and 271 guide the return flight of 65 the chain to a central idler 272.

65 70 The above described operation completes the cycle of operation and travel of a carrier and its board about the endless path 2. The carrier and board are then ready for transfer to one of the loading tracks 17 or 18 for reloading.

75 *The board conveying system and its drive (see FIGURES 1A, 1B, 5, 6, 7, 16, 21, 23, 24, 27, 40 and 41)*

75 76 The various conveyor chains for advancing the carriers 3 along the endless path 2 are divided into two groups,

each of which is independently driven, and the operation of the conveyor system is initiated by a programming cam 273 in the controller 13. One group consists of the return conveyor 268, the transfer chain 49, and the loading chains 62 and 63. The other group consists of separating chain 143, transporting conveyor 154 for carrying the boards to the inspection station, and the conveyor 167 which moves the boards through the measuring station and stripping area. The memory drum 15 is also geared to the drive for this latter group.

The return and loading group are interconnected by a drive chain 274 which travels over sprockets 275, 276 and 277. Sprocket 275 is mounted on a shaft 278 which carries a bevel gear 279 in mesh with a bevel gear 280 on the shaft 65 driving the loading chains 62 and 63. Sprocket 277 is on a shaft 281 which also carries drive sprocket 270 of return chain 268. Meshing gears 282 and 283 on shaft 281 and a shaft 284 which carries drive sprocket 285 for transfer chain 49 completes the interconnection of the three conveyor systems of the group. The drive for the group is provided by a power cylinder assembly 286 fixed to frame 1, which has a double-ended piston rod 287 connected into the loading chain 62. The cylinder is double acting and provides an oscillating movement to chains 62 and 63. A one-way clutch 64 is provided on shaft 281 so that chains 62 and 63 may have a reciprocating movement while chains 268 and 49 will move step by step. The carrier-engaging dogs 68 on chains 62 and 63 are pivotally mounted and biased to carrier-engaging position similarly to dogs 122. This will allow the dogs to be depressed and ride under carriers on the chain when the chain is moved in a return direction. By this arrangement, the two chains, 62 and 63, advance the carriers on them simultaneously and by equal increments of movement. Operation of cylinder 286 in a carrier-advancing direction is initiated by closing of switch 288 by cam 273 in the controller. Movement of the chain is stopped by a lug 289, on idler sprocket 272 of return chain 268, striking a switch 290. This also reverses the operation of cylinder 286.

The second conveyor group consisting of separating chain 143, chains 154 and 167 are interconnected in much the same manner as the first group. Conveyor chains 143 and 154 are connected by meshing gears 291 and 292 on the respective shafts 147 and 158. The chains 154 and 167 are coupled by means of gears 293 and 294 on the respective shafts 157 and 169. The memory drum is connected to the system by a gear train 295 interposed between shaft 169 and the memory drum drive shaft 198. This group of conveyors is operated by a power cylinder 296 which is fixed to the frame and has its piston rod 297 connected to a drive chain 298 passing over sprocket 299 on shaft 169 and having its opposite end connected to a spring 300 fastened to the frame. Sprocket 299 is connected to shaft 169 by means of a one-way clutch 301 so that movement is imparted to the shaft when the chain 298 is drawn in one direction only. Cylinder 296 is operated when switch 288 is closed by programming cam 273. The movement is stopped by operation of previously mentioned switch 188 by a cam 303 mounted on shaft 168. When the cylinder power is shut off, spring 300 will return the chain to its original position.

By having the two power cylinders 268 and 296 operate upon closure of switch 288 by programming cam 273, the two groups of conveyors can be strated together. By having the movement of the two groups stopped independently by cams moving in unison with the conveyors, each group is assured of a predetermined measured step of movement. Thus, all of the carriers about the path 2 will be moved simultaneously through equal steps of advancing movement.

Controller 13 contains the conveyor programming cam 273 which is mounted in a shaft 304 driven by a motor 305. This shaft leads into a gear box 306, which has a

driven output shaft 307 containing two retort programming cams 308 and 309. Shaft 307 rotates at one-half the speed of the shaft 304 to turn the cams 308 and 309 at one-half the speed of cam 273. The retort cams have recesses 310 and 311 into which the operating arms of switches 312 and 313 drop each revolution of the cams. As the boards are transferred to the loading tracks in alternation, it will require twice the number of steps of advance of the conveyor system to bring a predetermined number of boards to either loading track. By having the cams 308 and 309 rotate at half the speed of the conveyor programming cam 273 and orienting the cams 308 and 309 on shaft 307 so that the recesses 310 and 311 are oppositely disposed, one of the switches 312 and 313 will be operated when the required number of boards have accumulated on one track for loading in one retort and the other when the required number have accumulated for loading into the other retort. The operation of switches 312 and 313 are the signals previously mentioned which are required together with closure of switches 85 and 86 as groups of assembled carriers and boards are moved onto the shiftable track, to cause the retort doors to open. By requiring the signals from the controller for opening the retort doors, the operation of the doors in proper sequence with the conveyor movement is assured.

Carriers (see FIGURES 37, 38 and 39)

The carriers 3 are designed for quick placement on, and removal from, the rails of the track forming the endless path 2, and for close nesting in groups. They have rotatable board-supporting members, automatically rotatable by the guides 56 and 163 to properly orient the boards for certain operations. Each carrier consists of a carrier body 314 and the board-seating members 53. The body has oppositely projecting roller-mounting members 315 at the bottom, and similar members 316 at the top. There are four rail-engaging rollers 317, and each is rotatably mounted at one end of a spring mounting arm 318. The opposite ends of the spring arms are connected to the mounting members 315 and 316. It will be noted from FIGURE 37 that the rollers are oppositely arranged on opposite sides of the body. The roller that rides upon the upper side of one rail is projected forwardly from the body, while the roller that rides upon the upper side of the other rail is projected rearwardly from the body. The same is true of the rollers riding on the lower sides of the rails, and there is one forwardly and one rearwardly projected roller for each rail with one engaging the upper side of the rail and the other the lower side. This arrangement provides a very stable mount for the carrier, permits easy removal from the rail by a simple rotative movement, and allows close nesting of the carriers in a group. The body has a chain abutment 319 secured at the bottom and projecting downwardly into the path of the dogs on the conveyor chains.

The top of the carrier body carries a vertical post 320 upon which the board-support 53 is mounted. The board-support has a central opening 321 to receive the post 320 to provide the swivel mount 55. There is a longitudinally extending groove 322 to seat the board 4. The board-support is rotatable upon post 320 and held in positions of rotative adjustment by means of leaf springs 323, secured at one end to seats 324 on opposite sides of the body and having their free ends contacting a polygonal projection 325 on the bottom of the board-support. The polygonal projection 325 has faces for seating the leaf springs when the board-support is parallel to the path of travel of the carrier and when it is at right angles and at 45° to that position. The guide roller 54 depends from one side of the board-support to engage the orienting guides 56 and 163 and rotate the board-support from one position to another.

Electrical operating controls (see FIGURES 42 and 43)

As previously described, overall control of movement of the transporting conveyor system and the operation of

the retort doors is had through the cams 273, 308 and 309 in the controller 13. Operation of the various power cylinder assemblies is initiated and stopped by the numerous limit switches which have been mentioned. These switches can be arranged in circuits in many different ways well known to those skilled in the art. In order to complete the disclosure however, practical circuits have been shown and will be briefly described.

In FIGURE 42, a circuit for controlling the return line, transfer carriage and loading lines is shown. The circuit includes the power line 326 and return line 327, with the control lines bridged across them.

The power cylinder 286 is operated to advance the conveyor lines by closure of switch 288 by cam 273 in the controller 13. Switch 283 is in a line 323 from power line 326 which includes a valve-operating solenoid 329 to connect cylinder 286 to a fluid line (not shown). Cylinder 286 is reversed to stop the chain-advancing movement by operation of switch 290 by lug 289 on sprocket 272. Switch 290 is in a line 330 which includes the coil of a time delay relay 331. A branch line 332 around the relay coil includes a reversing solenoid 333 for cylinder 286 and contacts 334 of the time delay relay. This will operate to reverse the cylinder, but will break the reversing circuit after an interval so that the cylinder will be operative for chain-advancing movement upon the next operation of switch 283.

The operation of the transfer carriage 28 by cylinder 37 is controlled by switches 44 and 45 struck by carriers moving onto the respective tracks of the transfer carriage. Switch 44 is in a line 335 with solenoid 336 for extending cylinder 37, while switch 45 is in a line 337 with solenoid 338 for retracting the cylinder.

Board-ejecting cylinders 47 and 51 are extended by switches 46 and 50 arranged in parallel in lines 339 and 340 with cylinder extending solenoid 341. The cylinders are retracted by switches 48 and 50 in parallel lines 342 and 343 with solenoid 344.

After the boards have been loaded and accumulated, the group is moved to and through the retort station. The means for moving them are controlled by the circuitry shown in FIGURE 43. The various circuits are bridged from the power line 326 to the return line 327.

It will be remembered that when a predetermined number of carriers with loaded boards have accumulated at the accumulation station at the end of tracks 17, switch 73 is closed. This switch is in a line 345 which includes a control relay 346, and the relay will be energized when the switch is closed. Energizing the relay will cause relay contacts 347 in a line 348 to close, setting up a holding circuit for relay 346 to keep it energized after the group of carriers have been moved and switch 73 reopens. A second set of contacts 349 of relay 346 also close completing a circuit through line 350 and a valve operating solenoid 351 which allows fluid under pressure to flow to power cylinder 75 to cause that cylinder to retract its piston rod to draw the accumulated group of carriers onto the shiftable track section 71. When the carriers are on track 71, a switch 85 is operated to break the holding circuit to relay 346 and thus deenergize solenoid 351. The valve controlling cylinder 75 can be spring biased so that when the solenoid is deenergized the valve returns to its opposite position to cause cylinder 75 to operate in the opposite direction and return to its position of rest.

Operating switch 85 also closes a circuit through line 352 to energize a relay 353. Relay 353 has normally closed contacts 354 in line 355 which, in conjunction with normally closed contacts 356 in line 357 of a relay 358 provides a second holding circuit for relay 346. This circuit is broken by energizing relay 353, and a holding circuit for relay 353 is set up through contacts 359 of that relay. Another set of contacts 360 of relay 353 are closed to complete a circuit through line 361 to a relay 362. This circuit is closed only if the retort program timer cam 308 in controller 13 has closed its switch 312 which is located

in that line. The energizing of relay 362 closes its contacts 363 in line 364 to the retort door motor relay 365 to operate the door motor to open the retort door. This circuit includes contacts 366 of a relay in the opposite retort which is energized when the door of that retort is closed to prevent opening of the door of one retort while the door of the other is open. If contacts 366 are closed, this will start the retort door opening movement.

When relay 363 is energized several other circuits are closed or set up for closing. Contacts 367 of relay 362 are closed which completes a circuit through line 368 to control relay 369. This causes contacts 370 and 371 of relay 369 to close completing a holding circuit for that relay through line 372. This line is fed from power line 326, through a branch line 373. Contacts 374 of relay 369 also close, completing a circuit through line 375 to a control relay 376. Energizing relay 376 closes contacts 377 in line 378 to establish a holding circuit for the relay, and closes contacts 379 in a line 380 to set a circuit through a valve solenoid 381 for later closing.

When the retort door has reached a fully open position in alignment with the unloading track 94, it strikes and moves switch 95 which breaks the circuit to control relay 362 causing its contacts 363 in the motor relay line 364 to open and stop the door movement. The operation of switch 95 also completes the circuit through solenoid 381. This serves to operate power cylinder 100 to move discharge carriage 96 into contact with the door track and to operate power cylinder 130 to move unloading track 94 into contact with the door track. When track 94 moves it allows switch 1001 to close actuating a solenoid valve 1002 to extend cylinder 140. The arrival of the two discharge carriage and unloading track at the door will operate switches 108 and 109 in line 372 to complete a circuit through a valve solenoid 382 to cause discharge cylinder 103 on carriage 96 to operate to push the carriers on the retort door track onto the unloading track 94.

When the carriers are on track 94, switch 110 is opened, breaking the circuit to solenoid 382, and the holding circuit to relay 369, thus reversing the movement of the discharging cylinder 103. When cylinder 103 is fully retracted, switch 111 is actuated which breaks the circuits to relay 376 and consequently the circuit to solenoid 381 causing the discharge carriage and unloading track to move away from the retort door.

Upon reaching their retracted positions, discharge carriage 96 and unloading track 94 will close switches 112 and 113 and open switch 1001. Before switch 112 was actuated, it was closed in a circuit through line 383 to a control relay 384. This closed contacts 385 in line 386 to establish a holding circuit for relay 384, and closed contacts 387 in line 388 which includes switch 113 and a motor relay 389 for moving the retort door in a closing direction. Thus, when switches 112 and 113 are operated the retort door begins a closing movement.

The energizing of relay 384 also closed contacts 390 in line 391 to a control relay 392. Energizing relay 392 closed its contacts 393 in line 394 to complete a holding circuit for relay 392, and closed contacts 395 setting up a circuit through line 396 to a valve operated solenoid 397 for later operation. When the retort door reaches alignment with shiftable track section 71 it strikes switch 114. This breaks the holding circuit to relay 384 causing contacts 387 to open and break the motor relay circuit and stop the door. At the same time, switch 114 closes with line 396 to energize solenoid 397 which causes power cylinder 117 to move shiftable track 71 with its carriers into contact with the retort door track.

The arrival of the shiftable track at the door closes switch 118, which is in a line 398 branching from line 396 and includes a valve solenoid 399 for controlling movement of the charging cylinder 119. Energizing the solenoid causes the cylinder to extend and push the carriers from the track 71 onto the door track. When the cylinder 75 is fully extended switch 124 is operated to break the hold-

ing circuit to relay 392 and open contacts 393 to de-energize solenoids 397 and 399 to retract the shiftable track 71 and the charging cylinder 119. As the track and cylinder move back the switch 124 returns to its former position.

When switch 124 is operated it closes a circuit through line 400 to a control relay 401. This closes relay contacts 402 in line 403 to establish a holding circuit for relay 401, and closes contacts 404 in line 405 to set up a circuit through motor relay 389 to again start the retort door to moving toward closed position when the circuit is closed. The carriage closes switch 125 when it reaches retracted position, and this completes the motor relay circuit.

As the door closes it operates switch 126 to complete a circuit through line 406 and a control relay 407. This opens normally closed contacts 408 in line 403 to de-energize relay 401, which, in turn, opens contacts 404 in line 405 and stops the door motor. It also closes contacts 409 in line 410 and energizes the relay 358 which opens its normally closed contacts 356 in the holding circuit line for relay 353 to deenergize that relay. Relay 353 also controls the beginning of the retort steam cycle.

When relay 407 is energized it closes contacts (not shown) in an identical circuit for the other retort. These contacts are the equivalent of the contacts 366 in the disclosed circuit. Of course, when the retort door again opens switch 126 will move back to its original position breaking the circuits to relays 407 and 358, resetting the circuits for another cycle.

*Measuring control and logic and stripping station circuits
(see FIGURES 44, 45A, 45B and 46)*

As previously described, the measuring of the stockings at the measuring station 10 is done by scanning with electric eyes, with a change in signal being given when the light reflected to the electric eyes passes from the polished metal board 4 into the stocking welt. Both sides of the board and stocking are scanned to determine variation between the welt tops on opposite sides of the stocking.

The upper and lower photo-electric heads 177 and 178 are identical. Each head consists of a housing 411 having an opening 412, with a photo-cell 413 and lamp 414 within the housing and the lamp rays focused through opening 412 by means of a lens 415 to a point on the aboard for reflection to the photo-cell. The lamps of the two heads receive their power from a power source 416. The photo-cells are independently powered and their signals amplified by connection of the photo-cell in head 177 to an amplifier and relay 417, and connection of the photo-cell in head 178 to an amplifier and relay 418. The amplified signal from photo-head 177 is carried to a commutator brush 419 which moves over contacts 420 of commutator 192. The amplified signal from photo-head 178 is carried to a second brush 421 which moves over a second set of contacts 422 in the commutator. It will be recalled that the brushes are mechanically coupled to the photo-heads and will move over the commutator contacts as the photo-heads move over the boards and stocking welts.

The commutator contacts 420 and 422 are composed of groups of conductive segments 423 insulated from each other, with the segments being accurately positioned on predetermined centers. Each segment is connected into the length classification computor logic circuits, to be described by a line 424.

As the photo-heads begin their stroking-measuring movement they are over the polished board and will receive a strong reflection of the lamp beam. When the scanning head moves over the stocking edge the intensity of the reflected beam drops sharply and the photo-cell output changes sharply. The photo-cell amplifiers differentiate between the two photo-cell outputs and send signals by the relays to the commutator brushes for transmission through the commutator segments the brushes are contacting to the computor circuits. When the photo-heads

are over the board a "Yes" signal is generated, and when the photo-heads pass over the stocking edge the signal will be a "No." Thus, a "yes" signal will be transmitted continuously to the logic circuits while the photo-cell is over the board and the "no" signal will commence when the photo-cell moves over the stocking, with the point of change being signalled by the commutator segment with which the brush is in contact at the time of change.

The point in the travel path at which the signal change occurs determines the length of the stocking and sets into operation the mechanism for stripping the stocking from the board when the stripping station for that length is reached. It must be borne in mind that when the two sides of the stocking are not the same length the signal change in the two photo-cells will not coincide. If the signal change from the two heads occurs within an acceptable interval, the stocking will be accepted for the particular measured length. If the signal changes are too widely separated, the stocking is rejected and mechanism is set up to remove the stocking at the reject stripping station.

Actually, if the two sides of the stocking are of different length the longer side determines the length classification and the shorter side the acceptability of the stocking. For example, if it is assumed for purposes of disclosure that the commutator segments are set on one-eighth inch centers and each length classification comprises two segments, then segments C and D can represent one length classification, E and F the next, etc. If we also assume that a length differential equal to three segments is acceptable, then if the longer side of the stocking signal is received at the time brush 419 is contacting C segment of the contacts 420, a signal for the opposite side when brush 421 is contacting either C segment, B segment or A segment of the contacts 422 will result in acceptance of the stocking for the C and D length classification.

Referring now to FIGURE 46, the logic diagram for length classification in accordance with the above program is shown. The commutator segments are divided to provide a "Too Long" class, then one-quarter inch plus increments to a "nominal," followed by one-quarter inch minus increments to a "Too Short" class. This provides eleven classes which, together with the reject class account for the twelve categories of classification, with stockings of each classification to be removed at one of the twelve stripping stations. For purpose of disclosure the segments of contacts 420 are indicated in FIGURE 46 by the letters shown on the segments in FIGURE 44 followed by the numeral "1" and those of contacts 422 by the letter followed by the numeral "2." Thus "C1" means segment "C" of the group 420, while "C2" means segment "C" of the group 422.

Returning to the example given above of the C, D, classification, it will be seen on FIGURE 46 that this represents the acceptable length variation for stocking classification "-1 inch." The computor circuits are set up so that if the signal change is registered at C1 or C2 and the companion signal is not less than A1 or A2 the signal will be accepted unless there has been a previous reject signal sent manually by the inspector. The reject signal disables the otherwise acceptable combination.

On the left side of FIGURE 46 the combinations of signals determining the various length classifications are shown, while on the right are shown the reject combinations for these classifications. For example, a C1 or C2 signal but not an E1 or E2 will classify the stocking as "-1 inch," while an E1 or E2 signal but not a G1 or G2 will classify the stocking as "-three-quarters inch." Referring to the opposite side of the logic diagram it will be seen that a C2 and a X1 will result in a reject. Therefore, a C2 and a C1, B1 or A1 will be acceptable, as mentioned above.

Although the group of reject combinations have been shown divided into four groups each feeding a separate

"or" circuit, with the four "or" circuits feeding into a single "or" circuit to minimize circuit loading, all combinations could feed into a single "or" circuit. The output from the reject "or" circuit and from the eleven length classification circuits are fed into a battery of relays that control the setting of the switch-actuating fingers 201, 202, 203, 204, 205 and 206 of the memory drum, which serve to actuate the proper stripping station when the stocking arrives at that station. The eleven acceptable output lines of the logic system are indicated by the reference numerals 426 to 435, inclusive, and the reject output line as 436. (see FIGURES 45A and 46.)

The lines 425 to 436, inclusive, lead, respectively to one side of the coils of logic transfer relays 437 to 448, inclusive. (See FIGURE 45A.) The opposite sides of the coils are all connected to a common lead 449 which is connected to one side of a bridge rectifier 450 in the power line. All of the relays are identical and all have normally closed contacts in circuit with the solenoids they control. In this way, all of the solenoids will be normally energized. As previously described, the energized solenoids hold down the plungers which actuate the switch operating fingers of the memory drum, and when a solenoid is deenergized its plunger rises under spring pressure to throw the finger it controls into operative position. The solenoids are deenergized when the relays which control them receive the proper signals from the logic circuits. Thus all of the solenoids will remain energized until one of the acceptable length classification output lines 425 to 435 or the reject output line 436 sends a signal to its relay, whereupon the coil of that relay will be energized and its contacts will open to deenergize the solenoids it controls.

As previously mentioned, by using the memory drum switch operating fingers in pairs it is possible to limit the number of fingers to six. Thus, six solenoids are required, and each relay controls two solenoids. The diagram shown is connected for the following relay-solenoid combination.

Relay:	Solenoids
437	217-221
438	218-219
439	217-220
440	216-221
441	217-219
442	216-220
443	217-218
444	216-219
445	220-221
446	216-218
447	219-221
448	218-220

As all of the relay-solenoid circuits are essentially the same, only one will be described.

When a stocking of "Nominal" length has been scanned and there has been no rejection signal, the coil of relay 442 will be energized through line 430, which will cause the relay contacts 451 and 452 to open, breaking the circuits to solenoids 216 and 220 controlled by relay 442. The circuit for solenoid 216 is from the power line 326 through lines 453 and 454 to binding post 455 of relay 446, through the normally closed contacts of that relay to binding post 456, then through lines 457 and across relay 444 through the contacts between binding posts 458 and 459, line 460 to binding post 461 of relay 452, contacts 451, line 462 to binding post 463 of relay 449, binding post 464 and line 65 to solenoid 216. Solenoid 216, as are all the solenoids is connected to return line 237 by wire 466. The circuit for solenoid 220 is from power source 326 by wires 453, 467 and 468, the closed contacts of relay 448, wire 469, closed contacts of relay 445, line 470 to the binding post 471 of relay 442, closed contacts 452, line 472, closed contacts of relay 439, line 473 to solenoid 220, and line 466 to return line 237.

When the solenoids 216 and 220 are deenergized the plungers 207 and 211 which they control will be released to spring upward and set the fingers 201 and 205. These fingers are in the path of the pair of switches 228 and 229 in the lanes 230 which control the stripping mechanism for stockings of "nominal" length.

After the fingers are set the memory belt moves in equal increments simultaneously with the conveyor movement. As previously described, the action of the stripping station commences as the board bearing the stocking to be stripped begins its movement from the next preceding station to move to the selected stripping station. The conveyor movement is started by closure of switch 288 by programing cam 273 in controller 13, and stopped by closure of switch 188 by cam 303. Switches 288 and 188 are arranged in parallel circuit 474 and 475 across lines 476 and 477 leading from power and return lines 326 and 327. Circuit 474 contains solenoid 478 to shift the control valve of cylinder 296 to retract the piston, while circuit 475 contains solenoids 479 to cause the cylinder to extend.

The closing of switch 188 actually causes reversal of the cylinder action by energizing a relay 480 in a line 481 bridging a line 482 from line 475 and line 477 to the return line. Relay 480 has time delay contacts 483 in line 475 which close upon energization of relay 480 to complete the circuit to solenoid 479 to stop the conveyor movement. Contacts 483 reopen after a brief period, however, to deenergize the solenoid 479 and leave the cylinder valve free for shifting when switch 288 is closed.

When switch 188 is closed a number of stripper controlling relays 484, 485 and 486 are energized. These relays are in lines 487, 488 and 489, respectively, bridged across lines 482 and 277. Each of these relays has four sets of normally closed contacts and four sets of normally open contacts, with one of each set used in the circuits for four strippers. Thus, the three relays control the twelve strippers.

Before describing the strippers, it should be mentioned that the solenoid 490 for actuating the scanning cylinder 183 is in a line 491 bridged across lines 482 and 477, and is actuated when switch 188 is closed to stop the conveyor. Limit switch 186 opens the circuit and allows the scanning head to return. The energizing of relay 480 closed contacts 492 and 493 in line 494 leading to bridge 450 and in a logic reset circuit 495. Line 494 to the bridge is closed by limit switch 496 when the scanning head reaches its limit of scanning movement. The stripper circuits are all arranged in parallel across the lines 326 and 327. Each circuit includes a line 497 containing a relay 498, a line 499 with a solenoid 500 for extending the stripper cylinder 236 to carry the stripper head out to the stocking foot, and a line 501 with a solenoid 502 for closing the gripper jaws 239 and 240 from which a branch line 503 extends carrying a solenoid 504 to inflate the gripper pads 243. The pair of switches 228 and 229 in the memory drum controlling the particular gripper are arranged in series in line 497 so that upon closing of these switches relay 498 will be energized.

It will be remembered that switches 228 and 229 are closed as the Board begins to move from the preceding station to its stripping station. Thus, relay 498 is energized while the conveyor system is moving. Relays 484, 485 and 486 will not be energized at this time. Therefore, the normally closed contacts 505 of relay 484 (for example) are closed. When relay 498 is energized its contacts 506, in line 507 leading to lines 499, 501 and 503, are closed and a circuit is completed to solenoid 500 to start the gripper head moving outward. At the same time, contacts 507 of relay 498 are closed to complete a holding circuit for relay 498 through line 508. The gripper will move out and be in position with jaws open when the stocking arrives at the station. When switch 188 is closed to stop the conveyor, relay 484 will be energized closing its contacts 509 in circuit with jaw closing and pad inflating sole-

noids 502 and 504 so that the pads inflate and the jaws close. The normally closed contacts 505 will open to break the circuit to solenoid 500 so that the gripper head will start back, drawing the stocking from the form. As the gripper head approaches its position of rest, it strikes, and opens, switch 257 which breaks the circuit to relay 498, causing its contacts 506 and 508 to open. When contacts 506 open the circuits to solenoids 502 and 504 are broken and the jaws will open releasing the stocking and the jaw pads deflate. As soon as the conveyor system begins its next movement, switch 188 will open and break the circuit to relay 484 (and relays 485 and 486), whereupon contacts 505 will again close and contacts 509 will open.

This completes the control system. In view of the fact that each station and the operation which takes place there have been explained in detail, it is not necessary to make a review of the entire operation.

While in the above one practical embodiment of the invention has been disclosed, it will be understood that the details of construction described and shown are merely by way of illustration, and the invention may take other forms within the scope of the appended claims.

What is claimed is:

1. A boarding range for knit articles comprising, means defining an endless path, a plurality of carriers supporting boards movable on the path, means to move the carriers along the path to a plurality of stations including, a loading station where knit articles are pulled on boards on the carriers, a processing station, a stripping area having a plurality of stripping stations arranged in series along the path, means at each stripping station to grip and strip articles from boards, a measuring station located on the path anteriorly to the stripping area relative to the direction of movement of the carriers on the path and having means to determine the lengths of articles on the boards, and means operated by the length-determining means upon determination of an article length to select a stripping station for removal of the measured article from the board and to activate the article gripping and stripping means at the selected station to grip and strip the article from the board when the measured article arrives at the selected station.

2. A boarding range for knit articles as claimed in claim 1 wherein, there is a processing chamber at the processing station adjacent the endless path, the processing chamber having a carrier-receiving member movable to the endless path to become a part thereof and into the processing chamber for processing knit articles loaded on boards on carriers on the carrier-receiving member, means to move the carrier-receiving member to the endless path and to the processing chamber, and means to move carriers with loaded boards onto the carrier-receiving member for processing and from the carrier-receiving member for continued movement about the endless path.

3. A boarding range as claimed in claim 2 wherein, there are means to accumulate carriers into groups prior to movement onto the carrier-receiving member of the processing chamber, and means to separate carriers singly from the group for arrangement in spaced relation on the endless path after removal of a group from the carrier-receiving member.

4. A boarding range as claimed in claim 3 wherein, there is an inspection station adjacent the endless path positioned before the measuring station relative to the direction of travel of carriers about the endless path, one of said stripping stations being a reject stripping station, and manually operated means at the inspection station to activate the reject gripping and stripping means at the reject station when the article being inspected arrives at the reject stripping station and to disable the stripping station selection means operated by the length-determining means during the length determining operation for the rejected article.

5. A boarding range as claimed in claim 4 wherein, the endless path is divided into a pair of parallel paths at the

loading station, means to transfer carriers in alternation to the parallel paths, and a second processing chamber, the first-mentioned and second processing chambers being located one adjacent each parallel path.

5 6. A boarding range as claimed in claim 5 wherein, there are means adjacent the loading station to orient boards on the carriers at the loading station in predetermined position, and means intermediate the processing chambers and the inspection station to re-orient the boards in predetermined position.

10 7. A boarding range as claimed in claim 6 wherein, the means defining an endless path is arranged to hold the carriers with the boards supported thereon in vertical position from the stripping area through the processing chambers, and in horizontal position from the inspection station through the stripping area, means intermediate the processing chambers and inspection station to rotate the carriers to shift the boards from vertical to horizontal position, and means intermediate the stripping area and the loading station to rotate the carriers to shift the boards from horizontal to vertical position.

15 8. A boarding range as claimed in claim 7 wherein, there are means at each stripping station to move the gripping means into position to grasp articles on boards on the endless path, means to move the gripping means away from the endless path to pull the article from the board, and means to cause the gripping means to release and drop the article.

20 9. A boarding range as claimed in claim 1 wherein, there is an inspection station adjacent the endless path positioned before the measuring station relative to the direction of travel of carriers about the endless path, one of said stripping stations being a reject stripping station, and manually operated means at the inspection station to activate the reject stripping station when the article being inspected arrives at the reject stripping station and to disable the stripping station selection means operated by the length-determining means during the length determining operation for the rejected article.

25 10. A boarding range as claimed in claim 9 wherein, there are means at each stripping station to move the gripping means into position to grasp articles on boards on the endless path, means to move the gripping means away from the endless path to pull the article from the board, and means to cause the gripping means to release and drop the article.

30 11. Apparatus for accumulating knit articles in lots of varied lengths with the knit articles in each individual lot being of the same length comprising, means defining a path, a plurality of article carriers movable along the path, a measuring station adjacent the path, an article stripping area having a plurality of article-stripping stations arranged in series along the path, means to move the carriers to the measuring station and to the article-stripping stations in sequence, means at the measuring station to determine the lengths of knit articles on the carriers, means at each article-stripping station to strip measured knit articles from the carriers, and means operated by the length-determining means upon determination of an article length to select an article-stripping station for stripping of the measured article and to activate the article-stripping means at the selected stripping station to strip the knit article from the carrier when the measured knit article arrives at the selected stripping station.

35 12. Apparatus for accumulating boarded knit articles in lots of varied lengths with the articles in each individual lot being of uniform length comprising, means defining a path, a plurality of carriers supporting boards with knit articles thereon movable on the path, a measuring station adjacent the path, a stripping area having a plurality of stripping stations arranged in series along the path, means to move the carriers to the measuring station and to the stripping station in the stripping area in sequence, means at the measuring station to determine the lengths of knit articles on the boards, means at each

stripping station to grip and strip articles from boards on the path at the respective stations, and means operated by the length-determining means upon determination of an article length to select a stripping station for removal of the measured article and to activate the article-gripping and stripping means at the selected station to grip and strip the article from the board when the measured article arrives at the selected stripping station.

13. Apparatus for accumulating boarded knit articles in lots as claimed in claim 12, wherein the means for determining the lengths of knit articles on the boards includes a scanning head movable longitudinally over boards at the measuring station along a course which includes a portion of the board uncovered by the knit article and passes over an edge of the article on the board, means for moving the scanning head along said course, and means for registering the point along the course where the scanning head passes from the uncovered board over the said article edge.

14. Apparatus for accumulating boarded knit articles in lots as claimed in claim 13 wherein, the course along which the scanning head travels is divided into a plurality of distance increments and the stripping area includes a stripping station corresponding to each distance increment.

15. Apparatus for accumulating boarded knit articles in lots as claimed in claim 14 wherein, there is a second scanning head with the first-mentioned and second scanning heads being mounted for movement over opposite sides of boards at the measuring station, with the two scanning heads having independent means for registering the respective points along the courses of travel at which the respective scanning heads pass from the uncovered boards over the article edges, the stripping stations including a reject stripping station, and means operative upon the respective scanning head registrations being operated beyond a predetermined distance to select the reject stripping station for removal of the measured article and to activate the gripping and stripping means at the reject stripping station to grip the measured article and strip it from the board when the measured article reaches the reject stripping station.

16. Apparatus for accumulating boarded knit articles into lots of varied lengths with the articles in each individual lot being of uniform length comprising, means defining a path, a plurality of carriers supporting boards with knit articles thereon movable on the path, a measuring station adjacent the path, a stripping area having a plurality of stripping stations arranged in series along the path, means to move the carriers to the measuring station and to the stripping stations in sequence, a scanning head at the measuring station movable longitudinally over boards at the measuring station along a course which includes a portion of the board uncovered by the knit article and passes over an edge of the article on the board, means to move the scanning head over said course, means operable to signal the point on the course at which the scanning head passes from the uncovered board over the edge of the knit article, memory means having stripping station activating means selectively responsive to said signal, means at each stripping station to grip knit articles and strip them from boards, and means coordinating the stripping station activating means and the means to move the carriers to cause the selected activating means to operate the article-gripping and stripping means at a stripping station corresponding to the selected activating means when the measured article arrives at the said corresponding stripping station.

17. Apparatus for accumulating boarded knit articles as claimed in claim 16 wherein, there are means for resetting the memory means after the gripping and stripping means at the selected gripping station have been operated.

18. Apparatus for stripping knit articles from boards following a boarding operation comprising, means de-

fining a path along which boards may be moved, a stripping station adjacent the path, means to move boards having knit articles thereon along the path, a gripper head at the stripping station, means to move the gripper head toward the board path, the gripper head having jaws to overlie opposite sides of the board when the gripper head is at the board path, the gripper jaws each having inflatable pads thereon to engage articles on the boards when the jaws are closed, means to close the jaws and inflate the pads when the gripper head is at the path, and means to retract the gripper head from the path after the jaws are closed.

19. Apparatus for stripping knit articles from boards as claimed in claim 18 wherein, there are means to open the jaws and deflate the pads after the article is stripped from the board to release the article from the gripper head.

20. In apparatus for conveying carriers along a path, a plurality of carriers each having a depending abutment, the carriers being constructed so that the abutments of adjacent carriers are spaced from one another when the carriers are arranged in contacting relation in a group, carrier-supporting means along the path along which the carriers may be moved, carrier-transporting means along the path having carrier abutment-engaging means movably mounted thereon in spaced relation, means to bias the carrier abutment-engaging means toward abutment engaging position, and a cam carried by each abutment-engaging means and projecting forwardly in the direction of travel of the carrier-transporting means, the cams having portions projecting above the tops of the abutment-engaging means to contact the abutments of a group of carriers to depress the abutment-engaging means below abutment engaging level, the cam projecting portions being spaced in advance of the abutment-engaging members a distance sufficient to hold the abutment-engaging members depressed during movement beneath a group of carriers but permitting the abutment-engaging members to rise to engage the abutment of the last carrier of the group in the direction of movement of the carrier-transporting means and move that carrier from the group.

21. In apparatus for conveying carriers along a path as claimed in claim 20 wherein, the cams are of spring metal and form the abutment-engaging biasing means.

22. A track for carriers including a pair of spaced rails, the track having a first section in which the spaced rails are in one plane and a second section in which the plane of the rails is rotated with respect to the plane of the first section, whereby the carriers will be held in one position on the first track section and in another position at an angle thereto on the second section, and a connecting track section joining the first and second section, the connecting section having a rigid straight rail connecting one rail of the first section with one rail of the second section, and a flexible rail connecting the other rails of the first and second section, whereby in travelling from the first rail section to the second rail section a carrier will be guided by the rigid connecting rail and the flexible rail can bend to conform to the carrier path during turning movement of the carrier.

23. A track for carriers as claimed in claim 22 wherein, the flexible rail section is of plastic material.

24. A carrier for travel along a pair of spaced rails and for supporting a board upon which a knit article is mounted comprising, a body, upper rail-follower mounts and lower rail-follower mounts on the body, the upper mounts carrying a forwardly projecting rail-follower for travel along the upper surface of one of said rails and a rearwardly projecting rail-follower for travel along the upper surface of the other of said rails, and the lower mounts carrying a forwardly projecting rail-follower for travel along the underside of one track and a rearwardly projecting rail-follower for travel on the underside of the other track, the rail-followers on opposite rails being oppositely disposed and spaced on opposite sides of the body.

25. A carrier as claimed in claim 24 wherein, the rail-followers are mounted on the ends of spring arms having their opposite ends connected to the rail-follower mounts on the body.

26. A carrier, as claimed in claim 25 wherein, there is a board support pivotally mounted upon the body and having a board seat therein.

27. A carrier as claimed in claim 26 wherein, there are means to yieldably hold the board support in positions of pivotal adjustment on the body.
